UNITED STATES PATENT OFFICE.

FRANK K. WOODWORTH, OF ROCHESTER, NEW YORK.

DESIGN FOR A BOTTLE.

47,062.

Specification for Design.

Patented Mar. 2, 1915.

Application filed December 10, 1914. Serial No. 876,589. Term of patent 7 years.

To all whom it may concern:

Be it known that I, FRANK K. WOODWORTH, a citizen of the United States, residing in Rochester, in the county of Monroe and State of New York, have invented a new, original, and ornamental Design for a Bottle, of which the following is a specification, reference being had to the accompanying drawing, forming part thereof.

Figure 1 is a side elevation of a bottle showing my new design; Fig. 2 is an edge view of the same; and Fig. 3 is a plan view of the same.

I claim:

The ornamental design for a bottle as shown.

FRANK K. WOODWORTH.

Witnesses:

W. G. BUTTON,
ELEANOR MCBURNEY.
